(57) **CLAIM**

The ornamental design for an in-store marketing sign, as shown and described.

DESCRIPTION

FIG. 1 is a front view of an in-store marketing sign showing my new design;

FIG. 2 is a left side view thereof;

FIG. 3 is a right side view thereof;

FIG. 4 is a back view thereof;

FIG. 5 is a top view thereof;

FIG. 6 is a bottom view thereof;

FIG. 7 is a front view of a second embodiment thereof;

FIG. 8 is a left side view of FIG. 7;

FIG. 9 is a right side view of FIG. 7;

FIG. 10 is a back view of FIG. 7;

FIG. 11 is top view of FIG. 7; and,

FIG. 12 is a bottom view of FIG. 7.

The unevenly spaced broken lines are for purposes of illustrating portions of the in-store marketing sign and form no part of the claimed design, while the evenly spaced broken lines represent scores that do form part of the claimed design.
